UNITED STATES PATENT OFFICE

2,529,632

WATER CLOSET CONSTRUCTION

Irving H. Russell, Oak Park, and James A. Sloan,
River Forest, Ill., assignors to Sloan Valve Com-
pany, Chicago, Ill., a corporation of Illinois

Application October 21, 1946, Serial No. 704,558

5 Claims. (Cl. 4—70)

1

This invention relates in general to water closet constructions and has for its object to provide a new and improved device of this type including a water closet bowl, a flush valve for flushing the closet bowl, and a housing arranged to conceal the flush valve.

An important object of the invention is to provide a new and improved housing for a flush valve on a water closet bowl in which the housing is removably supported on the flush valve in such a manner as to be centrally located on the water closet bowl irrespective of variations in the position of the flush valve with relation to the water closet bowl.

The invention has as a further object the provision of a housing attached to a water closet flush valve in which the housing is removably locked in position to prevent unauthorized removal.

A further object is to design a flush valve housing presenting a smooth hygienic exterior enclosing and concealing the flush valve as well as serving as a toilet article shelf in a bathroom.

This invention is in the nature of an improvement on Patent No. 2,257,135, issued September 30, 1941, to William E. Sloan.

Other objects of the invention not specifically enumerated will be apparent from the following description which together with the accompanying drawings illustrates sufficient details to enable the invention to be understood clearly.

Fig. 1 is a side view of the water closet combination;

Fig. 2 is a front elevation of Fig. 1;

Fig. 3 is a large scale cross-sectional side elevation of the housing and flush valve;

Fig. 4 is a front view along the line 4—4 of Fig. 3;

Fig. 5 is a fragmentary rear view of the housing showing the housing supporting and locking means;

Fig. 6 is a fragmentary view taken along the line 6—6 of Fig. 5;

Fig. 7 is a fragmentary view along the line 7—7 of Fig. 5;

Figs. 8 and 9 are side and front views of a modified form of the invention in which the housing is spaced from a wall surface; while

Figs. 10 and 11 are side and front views of a further modification.

In order to appreciate the invention, it must be understood that when a plumber installs a water closet bowl and fittings there are a num-

2

ber of variable factors which he must contend with in performing what is known as the roughing-in operations. For example, there may be considerable variation from the correct position in the location of the different elements of the water closet combination with relation to one another. These problems of installing a water closet combination are clearly pointed out and described in the aforesaid Patent No. 2,257,135, and a further detailed description therefore need not be pointed out here.

Referring to Figs. 1 and 2, the water closet bowl 1 is installed directly over a waste pipe 2, which is located by the plumber at what he determines is the approximate position that the bowl is to be installed, keeping in mind other considerations such as the dimensions of the floor and wall surfaces after they are finished and the approximate position of the bowl from the wall 3. Other variable factors to be contended with are the location of the inlet water supply pipe 4 with respect to the flush valve, and the connection between the flush valve and the bowl. The approximate location of the flush valve with respect to the bowl must also be roughly gauged. In accordance with the invention, a novel housing construction generally indicated at 5 is arranged to be positioned against the wall surface 3 and above the rear of the closet bowl 1 to conceal and protect the flush valve and other mechanism in such a manner that any number of variables in the position of the different elements will be concealed regardless of the fact that they may or may not be centrally located with respect to the closet bowl 1. The water closet bowl is provided with the usual seat and lid 6, which lid may be lifted up when the water closet is in use and is adapted to be pushed back to actuate the flush valve mechanism through the medium of the operating member 7 carried on the housing. As shown in Fig. 2, the housing 5 and the flush valve operating member 7 are situated above the water closet bowl 1 in the approximate center line 8 passing through the water closet bowl 1, in order that a symmetrical and pleasing appearance may be presented. The housing 5 rests at its lower end on top of a rearwardly extending portion 9 formed in the bowl 1.

Referring more particularly now to Figs. 3 and 4, the exact details of construction and operation of the flush valve 10 are described in detail in the aforesaid Patent No. 2,257,135, and need not now be repeated since they form no part of the present invention. The flush valve 10 is rigidly

mounted in position against the wall surface 3 by means of a pair of screws 11 passing through slotted openings of a mounting bracket 12, which is suitably secured to the rear of the flush valve 10. Flush valve 10 is provided with the outlet discharge tube 13 extending to the spud connection on the rear ledge 9 of the water closet bowl 1 in the usual manner. A throttle or stop 14 is connected with the inlet water supply pipe 4 to regulate the water input and has its outlet connected to the inlet of the flush valve 10 by means of a telescoping connection 14', there being universal ball joints at each end of the pipe 15, connected to the flush valve and to the throttle 14.

The housing 5 is provided with depending side portions 15 and 16, as seen in Fig. 4, embracing opposite sides of the bowl ledge 9, while the lower edge surface 17 of the housing rests on top of this ledge 9. These side portions 15 and 16 center the housing on the bowl ledge and prevent lateral displacement of the housing. The front face of the housing has an opening therein through which the operating member 7 extends in a position where it is adapted to contact the valve actuating member 18 on the flush valve 10 when the lid 6 is pushed against the member 7, in the position shown in Fig. 3.

The housing 5 may be made of any suitable material such as metal or molded plastic and is of a hollow trapezoidal shape having generally converging sides, a sloping front surface, a flat rear edge adapted to engage the wall surface 3 together with a top flat surface 19 suitable for use as a toilet shelf, if desired. The housing 5 completely encloses the flush valve 10, except at its bottom end at the rear of the bowl ledge 9 where access may be had to the throttle 14 for manual adjustment of the same.

As pointed out in the aforesaid Sloan patent, a number of variable factors in the positioning of the apparatus must be compensated for by the plumber. Among these are the location of the bowl 1 and the waste pipe 2 with respect to the wall 3; the mounting of the flush valve 10 against the wall 3 by mounting screws 11, which can be made only approximately in line with the center line 8 of the water closet bowl; the length of the discharge pipe 13 which is compensated for by sawing off a piece of the pipe entering the spud connection; the position of the inlet supply pipe 4 with respect to the throttle 14 and inlet of the flush valve 10, which is compensated for by the telescoping feature of the pipe 14', and the ball joints on either end of this pipe.

After all the foregoing connections have been made, the housing 5 is adapted to be placed in position to enclose the flush valve and associated elements in such a manner as to completely conceal them and to be fastened to the flush valve directly on top of the bowl ledge 9 regardless of the variations in the position of the flush valve with respect to the center line 8 of the closet bowl. The depending portions 15 and 16 of the housing 5 prevent lateral displacement of the housing 5 with relation to the bowl ledge and the front bottom edge 17 protrudes sufficiently outward from the wall surface 3 to compensate for variable distances of the position of the bowl 1 with respect to the wall 3, this overlapping being predicated upon the horizontal length of the discharge tube 13 extending to the spud connection of the bowl and the location of the waste pipe 2.

Referring now particularly to Fig. 5, this shows

in detail the means for fastening the housing 5 directly to the flush valve 10, and includes a generally flat plate or bracket 20, slidably attached to the rearward side of the housing 5 by means of a pair of headed studs 21 engaging the slots 22 in bracket 20, the construction being such that the bracket 20 has limited lateral sliding movement with relation to the studs 21. The studs 21 are firmly threaded into and held in position on the housing 5 by the protruding bosses 23, as seen best in Fig. 7, so that the bracket 20 is spaced a slight distance from the rear of the housing 5. The bosses 23 are provided with vertical projections to hold the bracket 20 flat and prevent it from wobbling on the studs 21. At the top end of bracket 20 there is formed a portion 24 at right angles to the surface of the bracket which is adapted to engage and hold an extension 25 of the operating member 7, for the purpose of holding the member 7 in position on the rear side of the housing 5. A protruding part of the member 7 extends through an opening in the housing through the front side thereof in the position shown in Fig. 3, so it can be operated by the toilet seat lid 6.

The housing 5 is removably positioned and directly fastened to the flush valve 10 by cooperating means including a slot 26 centrally located in the bracket 20, having a flared opening 27 arranged at the entrance of the slot 26. The slot 26 is adapted to slidably engage an adjustable mounting screw 29, threaded into a projection formed on the body of flush valve 10. The adjusting screw 29 is threaded inward a certain amount and then locked by the locking nut 30, the correct adjustment being such that the rear edge of housing 5 will just contact the wall surface 3 as the slot 26 engages the head of adjusting screw 29 as the housing is slid downwardly over the flush valve and contacts the ledge 9 of the bowl with the lower edge 17 of the housing. This variable adjustment therefore provides another compensating feature for correcting inaccuracies in the location of the flush valve 10 with respect to the wall 3 and the bowl 1. The bracket 20 and the housing 5 have a slight amount of resiliency inherent therein so that a fairly tight connection of the bracket with the adjusting screw 29 is assured and so the housing will not be loose and caused to rattle.

Referring again specifically to Fig. 5, it will be seen that as the housing is slid into position over the flush valve 10, and on the bowl ledge 9, the adjusting screw 29 engages the flared openings 27 of slot 26, and regardless of the lateral position of the flush valve with respect to the center line 8 of the bowl 1, the bracket 20 is automatically slid or shifted laterally to the left or right position with respect to the housing 5. This action is accomplished by the studs 21 in slots 22 slidably guiding the bracket 20 as it is shifted. The bracket 20 therefore automatically adjusts itself as the housing is placed in position, for any variation in the position of the flush valve with respect to the closet bowl 1, so that the housing 5 will always be positioned directly on the center line 8 with respect to the bowl 1. The depending portions 15 and 16 overlap the bowl ledge 9 and prevent lateral displacement of the housing when it is placed in the correct position.

The bracket 20 while being shiftable laterally a certain amount, will still maintain its turned up portion 24 in contact with the extension 25

of the operating member 7. Also this operating member is of sufficient width that slight lateral displacement of the flush valve 10 and its actuating member 18 will not put it out of path of engagement with the rear side of the operating member 7.

It will be seen that with the foregoing construction the housing automatically adjusts itself and compensates for any slight errors of the plumber in locating the supply and waste pipes and the flush valve so that the assembly can be made rigid without throwing the finished fixtures out of alignment. Furthermore, the housing is of such shape and contour as to harmonize pleasingly with the water closet bowl and because of its smooth exterior surface is readily maintained in a clean and hygienic state. The housing provides an effective enclosure for protecting and concealing the flush valve and other appurtenances and is at all time in perfect alignment with the center line of the water closet combination. It will be noted that when the housing is in position with its back edges against the wall and its bottom edge resting on the bowl ledge, the throttle stop 14 is readily accessible for adjustment and manipulation by a person reaching down behind the bowl ledge and grasping the adjusting handle on the throttle stop. Because the slight springing action of the bracket 20 in its engagement with the adjusting screw 29 permits a tight fit of the housing against the wall, the housing is not readily displaced or accidentally moved upward out of engagement with the adjusting screw 29, gravitational force assisting in holding the housing downward in position on the flush valve and bowl ledge. The housing provides an additional advantage in that by completely enclosing the top, sides and front of the flush valve and other appurtenances, the formation of condensation on the outside surfaces is prevented because this enclosure is only open at the bottom and no complete circulation or movement of air through the housing and over the relatively cold flush valve can take place. Therefore, the housing will not accumulate moisture and keep dripping on the bathroom floor, a customary objection of the tank type of water closet construction.

While the housing may be readily slipped into position over the flush valve on the water closet bowl and just as easily removed when desired, there are certain instances where it may be desirable that such action not take place, for example in public toilet rooms or where children may have access to the water closet combination and may tamper with the housing and adjustment of the flush valve or throttle 14. In such installations, it is desirable to lock the housing in position and the invention contemplates such an arrangement.

Referring to Figs. 5 and 7, an L-shaped locking lever arm 31 is provided, being pivoted near its midpoint by a rivet 32 attached to the bracket 20 and arranged in such a manner that a downwardly extending lever arm 33 may be accessible for manual manipulation. Normally due to the weight and length of lever 33 the locking device is maintained in the position shown in Fig. 5, with a stop pin 34 preventing rotation of the lever in a counterclockwise direction. As the housing is slid in place over the flush valve and the adjusting screw 29 passes into slot 26, the screw 29 has a passing contact with the end 31 of the locking lever tilting the lever, and when the adjust-

ing screw 29 is in the position as shown in Fig. 5, the locking lever resumes its normal hanging down position. When an attempt is made to remove the housing under these locking conditions, upward movement of the housing causes the end of locking lever 31 to engage the adjusting screw 29 and because of the engagement of stop pin 34 with lever arm 31, the housing is prevented from being removed from the flush valve. Unauthorized removal of the housing and possible damage or mal-adjustment of the flush valve is thereby prevented.

In order to remove the locking control from the housing, those persons who are cognizant of the manner of unlocking the device, which would ordinarily be a plumber or maintenance man, would reach underneath the open end of the housing 5 behind the water closet bowl, grasp and rotate the depending lever 33 in a clockwise direction (as viewed in Fig. 5) to the position shown by the dotted lines in Fig. 5. The end 31 of the locking lever is thereby rotated out of the path of the adjusting screw 29 sufficiently far so that the housing can be raised and adjusting screw 29 passed freely out of slot 26 and the housing be removed.

The locking action is entirely automatic, taking place at the same time that the housing is slid into position over the valve and no other action is required to lock the housing in place.

Referring now particularly to Figs. 8 and 9, there is shown a side and front view of a modification of the housing structure, as indicated at 35, to provide an arrangement in which the valve and housing under certain circumstances are spaced away from the wall surface 3, as well as the bowl, and the bowl is equipped with a top spud connection. In this arrangement, the rear ledge of the water closet bowl is provided with the top spud connection extending to the discharge outlet of the flush valve 37, and which flush valve is fastened by studs 38 and screws directly to the wall surface 3 and thereby rigidly held in position. The housing 35 is held in position on the bowl ledge and over the flush valve 37 by means of a threaded screw 39 passing through the flat top surface of the housing 35 and entering the top of the flush valve 37 as shown. The housing is thereby directly clamped on the bowl ledge and held in position on the flush valve, away from the wall surface 3 and not supported thereon. In this construction, there is no adjusting screw provided such as screw 29 on the flush valve 10, shown in Fig. 3, and the bracket 20 serves merely to support the valve operating member 7 in position. The flush valve 37 may be of the conventional type, but is equipped with an operating lever arm 40 having an adjustable button 41 on one end fulcrumed near its mid-point in the usual handle opening position 42 of the flush valve. At its lower end, the operating lever 40 is pivoted to a bracket 43 clamped to the discharge pipe of the flush valve.

When this flush valve is to be operated, the operating member 7 is pressed inward by the seat cover 6 contacting the adjustable button 41, so that the flush valve actuating member 42 is pressed inward to operate the flush valve. It is desirable in such an arrangement that the rear surface of the housing 35 be provided with a partial enclosure as indicated at 44 to provide further protection for the flush valve. The housing 35 is also provided with projecting portions 45 extending from the inside surface of the housing and adapted to rest on top of the rear bowl

ledge 36, as shown in Fig. 9. Depending portions 46 help to enclose the rear portion of the water closet bowl ledge. The foregoing type of housing 35 is adaptable for situations in which an existing valve has already been installed on the top spud of a water closet bowl and the valve can be readily modified by the removal of the usual manually operated handle and the addition of the operating lever 40, so that it can be operated through the operating member 7.

Referring now to the modification shown in Figs. 10 and 11, this shows a somewhat similar construction of a housing 47 partially enclosed at 48 for a top spud bowl spaced from the wall surface 3. In this construction, the top spud bowl is provided with a ledge 49 having openings therein through which the bolts 50 are adapted to pass. These bolts hold the housing 47 in place by means of the extensions 51 formed in opposite sides of the housing. The depending portions 52 of the housing serve to conceal the lower portion of the bowl ledge. Since the housing 47 is bolted directly to the bowl ledge 49, it is desirable that some means be provided to permit access to the flush valve 55 for adjustment purposes. This is provided by forming the top of the housing 47 so that a cover 53 can be placed directly over the opening of the housing and held in position preferably by one or more screws, such as 54. The cover 53 conveniently provides a shelf for toilet articles, if desired.

While several modifications of the invention have been disclosed and described, it is clear that the broad general principles are applicable to other variations, and it is therefore to be understood that the invention is not to be limited to the precise forms illustrated but only by the scope of the appended claims.

What is claimed is:

1. In a water closet combination, a water closet bowl, a flush valve for flushing the water closet bowl, together with a housing for concealing the flush valve, and means for fastening said housing directly to said flush valve, said fastening means comprising a bracket on said housing and an engaging member on said flush valve, said bracket having a vertical slot therein adapted to slidably engage said engaging member as the housing is placed over the flush valve, bracket supporting studs on said housing, said bracket having horizontal slots therein engaging said supporting studs whereby said bracket is free to shift horizontally as it is slid onto the flush valve to compensate for variations in the position of said flush valve with respect to said water closet bowl.

2. In a water closet combination, a water closet bowl having a flush valve thereon and a housing concealing the flush valve, means for removably supporting said housing on said flush valve comprising a bracket on said housing and a member on said flush valve slidably engageable by said bracket as said housing is placed in position on said flush valve, and means for automatically locking said housing on said flush valve as said housing is placed in position, said locking means comprising a lever pivoted to said bracket and having a long leg and a short leg, said long leg manually accessible for unlocking said lever, said short leg having passing contact with said flush valve member as the housing is slid over said flush valve, and a stop on said bracket engageable by said

short leg when an attempt is made to remove said housing without first pivoting said lever.

3. In a water closet combination, a water closet bowl having a flush valve thereon and a housing for concealing said flush valve, means for removably supporting said housing on said flush valve comprising a bracket on said housing having a slot therein, an adjustable stud on said flush valve slidably engaged by said bracket slot as said housing is placed in position on said flush valve, and means for automatically locking said housing on said flush valve as it is placed in position thereon, said locking means comprising a locking lever on said bracket having passing engagement with said adjustable stud as the housing is placed in position, said locking lever being engageable with said adjustable stud when an attempt is made to remove the housing from said flush valve, and an extension on said locking lever manually accessible from outside said housing to unlock said locking means.

4. In a water closet combination, a water closet bowl having a flush valve for flushing the same and a housing for concealing the flush valve, means for removably supporting said housing on said flush valve comprising a bracket on said housing having a vertical slot therein slidably engaging a stud on said flush valve as the housing is placed in position on said flush valve, means for loosely supporting said bracket on said housing comprising horizontal slots in said bracket slidably engaging studs on said housing, whereby said bracket is shiftable horizontally as said housing is placed in position on said flush valve and any slight variations in the fixed location of said flush valve with respect to said closet bowl is automatically compensated for, said housing having a bottom edge resting on said closet bowl together with depending side positions overlapping the sides of said closet bowl whereby the housing is centered on said closet bowl and lateral displacement thereof is prevented.

5. In a water closet combination, a water closet bowl having a flush valve for flushing the same and a housing for concealing the flush valve, means for removably supporting said housing on said flush valve arranged to automatically compensate for any slight variations in the fixed location of said flush valve with respect to said closet bowl as said housing is placed in position on said water closet, said means including a bracket having horizontal slots therein slidably engaging studs on said housing, together with a vertical slot in said bracket slidably engaging a stud on said flush valve, and said housing having a bottom edge resting on said closet bowl and depending side portions on said housing overlapping the sides of said closet bowl.
